UNITED STATES PATENT OFFICE.

CHAUNCEY D. BURRITT, OF CADILLAC, MICHIGAN.

RELISHING-MACHINE.

1,400,864.

Specification of Letters Patent. Patented Dec. 20, 1921.

Application filed April 25, 1919. Serial No. 292,734.

To all whom it may concern:

Be it known that I, CHAUNCEY D. BURRITT, a citizen of the United States, residing at Cadillac, county of Wexford, State of Michigan, have invented certain new and useful Improvements in Relishing-Machines, of which the following is a specification.

This invention relates to improvements in relishing machines.

10 The main objects of this invention are:

First, to provide an improved relishing machine in which the work is automatically carried to the cutters and effectively held while being acted upon by the cutters.

15 Second, to provide an improved relishing machine which is quickly adjustable to different classes of work.

Third, to provide an improved relishing machine in which the adjustment may be 20 easily accomplished by persons other than skilled workmen.

Fourth, to provide an improved machine of the class described which is of large capacity.

25 Fifth, to provide in a machine of the class described an improved conveyer.

Further objects, and objects relating to structural details, will definitely appear from the detailed description to follow.

30 I accomplish the objects of my invention by the devices and means described in the following specification. The invention is clearly defined and pointed out in the claims.

A structure which is a preferred embodiment of my invention is clearly illustrated 35 in the accompanying drawing, forming a part of this specification, in which:

Figure I is a front elevation of a structure embodying the features of my invention.

40 Fig. II is an end elevation looking from the right of Fig. I.

Fig. III is a detail rear perspective showing details of the conveyer and the work holding means.

45 Fig. IV is a detail front perspective showing further details of the conveyer and work-holding means and guides.

Fig. V is a plan view of the yielding work guide or end thrust member removed from 50 its supports.

In the drawing similar reference characters refer to similar parts throughout the several views.

Referring to the drawing, the main frame 55 of the structure illustrated comprises end members consisting of uprights 1 and cross-

pieces 2. These end members are connected by horizontal members 3. The frame is also provided with intermediate upright members 4 provided with crosspieces and supporting 60 the feed conveyer and other parts. At each end of the frame are spaced uprights 5 secured to the crosspieces 2 and projecting above the same. The uprights 5 have cross members 6 at their upper ends. 65

Mounted between these uprights 5 is a horizontally disposed head bar 7. This head bar is vertically adjustable, being secured in its vertically adjusted positions by means of the clamping bolts 8 arranged through the 70 uprights below the head bar to clamp the uprights thereon. The head bar is vertically adjusted by means of the screws 9 arranged through the crosspieces 6 and having threaded engagement with the head bar. 75

On the upper ends of these screws are sprocket wheels 10 connected by the sprocket chain 11, one of the screws being provided with an adjusting crank 12. By this arrangement both ends of the head bar are 80 simultaneously adjusted or raised and lowered.

The cutters 13, which are shown conventionally, are carried by head members 14 and 15 mounted upon the under side of the head 85 bar 7. The head member 15 is adjustably mounted to provide for the axial adjustment of its cutter. Clamping bolts 16 are provided for securing the head member 15 in its adjusted position and the screw 17 having 90 a hand wheel 18 is provided for the adjustment of the head member.

The head member 15 has a pointer 19, while the head bar has a scale 20 with which the pointer coacts. The head bar has a 95 pointer 21 and one of the uprights 5 has a scale 22 with which the pointer coacts.

The driving shaft 23 is mounted on the lower part of the frame, the shaft being provided with a driving pulley 24 and with 100 pulleys 25 and 26. The cutter shafts 27 have pulleys 28 connected to the pulleys 25 and 26 on the driving shaft by means of the belts 29. The belt tightener pulleys 30 are tensioned by means of the weights 31, so 105 that the raising and lowering of the head bar 7 does not affect the driving connections or does not require any readjustment of the driving connections.

The feed conveyer comprises sprockets 32 110 and 33, the shaft 34 of the sprocket 33 being extended to one end of the frame and pro-

vided with a sprocket wheel 35 by which it is connected to the driving shaft 33 or other source of power, not shown.

The upper reaches of the sprocket chains 36 travel upon the ways or supports 37 disposed between the sprocket wheels. The sprocket chains have work carriers consisting of the rigid flights 38 carried by spaced links and the coacting yielding spring 10 clamping members 39 mounted on links 37 in advance of the links 36 carrying the flights 38. These work clamping springs 39 are of a general A-shape, being secured to the links by their forward arms, and the 15 rear free arms being their work engaging arms.

As the flights and clamping members pass over the front sprockets 32 onto the upper reaches of the conveyer they swing toward 20 each other to clamp the piece of work, as 40, firmly gripping the same, so that it is carried along by the conveyer.

To hold the work firmly on the conveyer I provide rearwardly inclined presser bars 25 41 mounted at their forward ends on supporting arms 42 by means of the springs 43. Blade springs 44 are mounted on these arms 42 to press downwardly upon the rear ends of the presser bars. Screws 45 through the 30 arms engage the springs regulating the pressure of the bars. These arms are mounted upon the cutter head bar 7.

To further assist in holding the work while acted upon by the cutter preventing 35 chattering thereof I mount a spring 46 centrally between the presser bars, the spring being positioned so that it engages the work about the time the cutters begin to act thereon and presses and holds the same firmly 40 while being acted upon by the cutters. The necessary pressure could be provided by the presser bars 41 but by providing this additional work holder the necessary pressure at the desired point is provided without the 45 necessity for undue friction during the major part of the time while the work is carried along by the conveyer.

To position the work endwise I provide a yieldingly supported end thrust member 50 47 carried by the bar 48 mounted upon the cutter head member 15. Springs 49 are provided for the thrust member 47,—see Fig. V. The guide 50 is mounted at the other side of the conveyer, an adjusting screw 51 being provided for adjustably supporting it as desired.

My improved relisher is adapted to receive work from a tenoning or other machine automatically or the work may be fed thereto 60 by hand.

I have not shown my improvements in relation to any other machine as it will be readily understood that they may be associated with other machinery as desired.

65 My improved machine is of large capacity

and is readily adjusted to various classes of work as desired and is entirely automatic. I have illustrated and described my improvements in one embodiment which I have found very satisfactory. Various parts are 70 shown conventionally. I have not attempted to illustrate or describe other modifications and adaptations which I contemplate as I believe the disclosure made will enable those skilled in the art to which my invention 75 relates to embody or adapt the same as may be desired.

Having thus described my invention, what I claim as new and desire to secure by Letters Patent, is:

1. In a structure of the class described, the combination of a frame, a vertically adjustable cutter head bar, adjusting means therefor, cutter head members mounted on said head bar, one of said head members being 85 mounted for axial adjustment of the cutter, cutters carried by said cutter head members, a feed conveyer below said cutter head bar comprising sprocket wheels and sprocket chains, and work carriers, a pair of rearwardly inclined yielding work presser bars mounted on said cutter head bar to engage the work as it is carried rearwardly by the conveyer, a yielding work holder member mounted on said cutter head bar centrally 95 between said work holder bars to engage the work while it is acted upon by the cutters, a yielding end thrust member at one side of the conveyer carried by the adjustable cutter head member to engage one end of the 100 work as it is carried by the feed conveyer, and an adjustable work guide disposed at the other side of the conveyer to position the work.

2. In a structure of the class described, the combination of a frame, a cutter head bar, adjusting means therefor, cutter head members mounted on said head bar, cutters carried by said cutter head members, a feed conveyer below said cutter head bar comprising sprocket wheels and sprocket chains, and work carriers comprising flights projecting to receive the work and coacting A-shaped clamping springs mounted by their front arms on links in advance of the links 115 carrying the flights to engage the work as the flights and clamping springs pass over the front sprockets onto the upper reaches of the conveyer chains, and a pair of rearwardly inclined yielding work presser bars 120 mounted on said cutter head bar to engage the work as it is carried rearwardly by the conveyer.

3. In a structure of the class described, the combination of a frame comprising a pair of 125 spaced uprights and crosspieces thereon, a cutter head bar disposed between said uprights below said crosspieces, screws for vertically adjusting said head bar carried by said crosspieces, one of said screws being 130

provided with an adjusting crank, sprockets on said screws, a sprocket chain connecting said sprockets whereby said screws are simultaneously actuated for the adjustment 5 of said head bar, cutter head members mounted on said head bar, one of said cutter head members being adjustable, a screw for adjusting said adjustable head member, clamping bolts for securing said adjustable 10 head member in its adjusted position on said head bar, cutter shafts carried by said cutter head members, a driving shaft disposed below said cutter head members, driving connections for said driving shaft to said 15 cutter shafts comprising pulleys and belts, and tensioned belt tightener pulleys for said belts.

4. In a structure of the class described, the combination of a frame comprising a pair 20 of spaced uprights and crosspieces thereon, a cutter head bar disposed between said uprights below said crosspieces, screws for vertically adjusting said head bar carried by said crosspieces, one of said screws being 25 provided with an adjusting crank, sprockets on said screws, a sprocket chain connecting

said sprockets whereby said screws are simultaneously actuated for the adjustment of said head bar, clamping bolts disposed through said uprights for clamping said 30 head bar in its adjusted positions, and cutter head members mounted on said head bar.

5. In a structure of the class described, the combination of a frame, cutter heads, a feed conveyer below said cutter heads comprising sprocket wheels and sprocket chains, and work carriers comprising flights and projecting from the links on which they are mounted to receive the work and coacting 35 clamping A-shaped springs mounted by 40 means of their front arms on links in advance of the links carrying the flights to engage the work as the flights and clamping springs pass over the front sprockets onto the upper reaches of the conveyer chains. 45

In witness whereof, I have hereunto set my hand and seal in the presence of two witnesses.

CHAUNCEY D. BURRITT. [L. S.]
